US00D856899S

(12) **United States Design Patent** (10) **Patent No.:** **US D856,899 S**
Evulet et al. (45) **Date of Patent:** **** Aug. 20, 2019**

(54) **AIRFRAME FOR AN UNMANNED AERIAL VEHICLE**

(71) Applicant: **JETOPTERA, INC.**, Edmonds, WA (US)

(72) Inventors: **Andrei Evulet**, Edmonds, WA (US); **Tyler Smallwood**, Edmonds, WA (US)

(73) Assignee: **Jetoptera, Inc.**, Edmonds, WA (US)

(**) Term: **15 Years**

(21) Appl. No.: **29/625,624**

(22) Filed: **Nov. 10, 2017**

(51) LOC (12) Cl. **12-07**

(52) U.S. Cl.

USPC **D12/335**

(57) **CLAIM**

We claim the ornamental design for an airframe for an unmanned aerial vehicle, as shown.

DESCRIPTION

FIG. 1 is a front perspective view of an airframe for an unmanned aerial vehicle, showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

1 Claim, 7 Drawing Sheets
